UNITED STATES PATENT OFFICE

152,385

DESIGN FOR A PHONOGRAPH

Henry F. Wheeler, Richmond Heights, Mo., assignor of one-half to A. Edward Gross, Richmond Heights, Mo.

Application February 10, 1947, Serial No. 136,818

Term of patent 7 years

(Cl. D56—4)

To all whom it may concern:

Be it known that I, Henry F. Wheeler, a citizen of the United States, residing in Richmond Heights, in the county of St. Louis and State of Missouri, have invented a new, original, and ornamental Design for Phonographs, of which the following is a specification, reference being had to the accompanying drawing, forming part thereof.

Fig. 1 is a top view of a phonograph, showing my new design.

Fig. 2 is a front view showing one of the duplicate sides of the tone arm, or reproducer arm, which appears in the form of a railroad train.

Fig. 2 is an end view looking toward the right hand ends of Figures 1 and 2.

I claim:

The ornamental design for a phonograph, substantially as shown.

HENRY F. WHEELER.
